VALVE ACTUATOR

Theodore J. Beregh, Patchogue, N. Y.

Application April 22, 1937, Serial No. 138,337

9 Claims. (Cl. 137—145)

This invention relates to improvements in valve actuators, and has relationship particularly to means for preventing offset by spraying the printed sheets with non-offsetting fluid, and 5 in detail relates to the automatic timing device or trip for releasing the spray in proper amount at the right time.

Objects

10 The objects of the invention are to provide an improved timing or tripping device of the character indicated; to provide for accurate timing of the duration of the spray; to utilize valves now on the market and adapt the tripping mechanism to accommodate the requisite movement 15 of the valve stem for securing the desired spray; to provide a device which employs direct thrust upon the valve; to avoid any bending or twisting force upon the valve stem; to provide a snap trip so as to assure prompt and complete closing 20 of the valve; to enable the parts which constitute the snap trip to be made of hard metal and to have a relative adjustment for taking up wear that may occur between them; to operate the timing or tripping device from a moving part of 25 the press; to attain precision of tripping regardless of the precision of movement of the part of the press actuating the device; to provide few and easily replaceable parts; to secure simplicity of construction and operation; and to obtain 30 other advantages and results as may be brought out in the following description.

Drawings

Figure 1 is a side elevation of the essential 35 parts of a printing press to which my invention is applied;

Figure 2 is an elevation of the air compressor for use in obtaining the actuating medium for the spray;

40 Figure 3 is an elevation of the valve controlling the spray with the tripping or timing device of the present invention associated therewith;

Figure 4 is an edge view of the same showing the invention mounted upon a part of the press 45 shown in section; and

Figures 5 and 6 are views similar to Figure 3 with the tripping device shown in successive stages of operation in effecting the tripping and releasing of the valve stem.

50 Description

In the specific embodiment of the invention illustrated in said drawings, the reference numeral 10 indicates a conventional printing press of reciprocating type wherein carriage 11 moves

horizontally back and forth. It is not necessary to enter into a discussion of the various parts of the press or of its operation. Suffice it to say, as the carriage moves back and forth the cylinder thereon engages a form when moving in one direction, and is raised off of the form so as not to print when moving in the other direction, and after the paper is printed it is automatically removed or discharged and stacked upon a table 12. When the sheet is discharged upon the table 10 it is at the top of the stack, and in order to prevent offsetting of the ink between the top sheet and the next one to be applied, a spray 13 of certain non-offsetting fluid known in the trade 15 is applied to each sheet before another one is placed thereon. For this purpose a spray gun 14 is shown above the table 12, said gun receiving the non-offsetting fluid from a tank 15 or suitable source, the fluid being atomized and sprayed by air pressure entering the spray gun through an air supply pipe 16. The present invention relates particularly to the automatic opening and closing of a valve 17 situated in this air supply pipe 16.

20 However, before entering into a discussion of 25 the control, let it be said that a suitable source of air supply must be maintained, and this can be conveniently done as illustrated in Figures 1 and 2 by having a cylinder 18 axially parallel to the direction of movement of the carriage 11 30 and provided with a piston 19 therein actuated by a piston rod 20 connected to the carriage so that as the carriage moves back and forth the piston creates pressure in a storage tank 21 from which the pressure cannot return to the cylinder 35 because of interposed check valves 22. By this means, the press itself is self-contained in connection with the source of air supply, the air supply control and the gun using the air. However, the invention is not restricted to the particular source of air supply illustrated.

40 The particular timing or tripping mechanism employed in operating valve 17, preferably comprises the several instrumentalities illustrated 45 more in detail in Figures 3 to 6. In those figures it will be observed that a bracket 23 is provided one leg of which may be bolted to a fixed part of the press and the lower leg of which projects horizontally outward from the press with an appropriate opening therein for receiving the 50 neck of valve 17 which is locked in place by nut 24 with the stem 25 of the valve projecting upwardly at the upper side of the horizontal portion of the bracket. Above the stem is mounted 55 a horizontally disposed lever 26 pivoted at 27 to

a lug 28 projecting outwardly at one side edge of the upright part of bracket 23. Depression of the lever 26 will depress valve stem 25 and thus permit the flow of air through the valve. 5 It will thus be observed that since lever 26 and valve stem 25 are substantially perpendicular to each other and have only very slight motion to open the valve, that there is substantially no side thrust upon the valve stem and consequently 10 the lever introduces substantially no wear in the valve to which it would not ordinarily be subjected in any ordinary use. I am thus enabled to utilize a common construction of valve as found upon the market and require no special 15 construction of valve in the carrying out of the present invention wherein the valve is an element of the combination.

Mounted upon the lever 26 is an adjustable wear-piece 29 of angle iron formation lying flat-wise upon the top of the lever. The extremity of the wear-piece next the end overlying the valve stem is tapered downwardly inward so as to provide a sharp forward upper tripping edge 30. This tripping edge may be adjusted to any 20 position in its distance from the pivoting of lever 26 by virtue of slots 31 in the front face of said wear-piece and clamping screws 32 passing through said slots in the front edge of lever 26. By preference a hard metal, of which steel is 30 an example, is employed for the wear-piece so it will stand up under long usage and maintain a sharp tripping edge 30.

Immediately above the wear-piece 29 and within a short distance of the tripping edge 30 thereof is provided a stud 33 projecting from bracket 23 transversely over said wear-piece and constituting a stop to limit the upward movement of the lever. It will be understood that valve 17 contains a spring 34 which tends to lift the valve stem 25 which in turn tends to lift the lever 26 to bring the wear-piece substantially into engagement with said stop. However, it is to be understood that the primary function of said spring 34 is to seat the valve head 35, within the 40 valve 17, and therefore stop 33 is not intended to limit upward movement of the valve stem, but merely to prevent the lever from undue movement away from the valve stem when the valve stem is in its uppermost position. The said stud 50 33 has a face thereof away from the pivot end of lever 26 sloped downwardly forward toward the tripping end of the wear-piece, but with the plane of the slope of the stud intersecting the said wear-piece slightly back of the said tripping edge for purpose which will presently appear.

Above the said stud is a rocker member 36 which is pivoted, as by a stud screw 37, next its upper end to swing on an axis substantially above and parallel to the longitudinal dimension or axis 60 of stud 33. This rocker 36 provides a vertical socket or slideway within which is mounted a sliding bar conveniently referred to as trigger 38. This trigger has a lower converging lip 39 one tapered face of which is in constant engagement 65 with the tapered or sloping face of stud 33. The lower end of this converging lip provides a sharp corner adapted to slide along the upper face of the wear-piece and pass off the end edge 30 thereof. Here again, it is preferable to employ 70 a hard metal, such as steel, so as to prevent wear as much as possible and keep a sharp releasing edge on the trigger. By virtue of the tapering of said lip and said stud, downward depression of the trigger obtains an angular displacement 75 thereof in the direction toward the said end edge

30 of the wear-piece, as clearly shown in Figure 5. As soon as the lip passes off of said end edge of the wear-piece, the lever 26 may immediately be swung upwardly by virtue of the valve spring 34, and in doing so will cause the said end edge 30 5 to ride upwardly upon the tapered face of the lip of the trigger which is at that time ineffective in depressing the said lever.

The trigger is actuated downward by an appropriate moving part of the press, designated by reference numeral 40. Said moving part 40 of the press may accordingly have a considerable greater movement than the desired amount of depression for the valve, and the valve is not affected by any lack of precision in the length of 15 stroke of the said moving part of the press. On the other hand the amount of movement of the valve stem can be very precisely regulated, being made to remain open for a longer period, where such is desired, by projecting the wear-piece further beyond the stud 33, which will increase the time required for the trigger to clear the end edge of the wear-piece.

The rocker 36 is provided with a tension spring 41 which pulls the rocker laterally so as to maintain engagement of the trigger with the stud or with the end of the wear-piece in its several positions of operation. The trigger is provided with a spring 42 positioned at the upper end of the rocker interposed between said end and a washer 30 43 held from outward displacement on the upper end of the trigger by a pin 44 transverse of and through the trigger so that the tension of the spring will tend to raise the trigger and maintain its upper end always in contact with the said 35 moving part 40 of the press.

I desire particularly to call attention that lip end 39 of the trigger as shown in Figure 3 still remains in contact with the sloping face of stud 33 when the moving part 40 and trigger are in 40 uppermost position. While this is probably sufficient to prevent the rocker from having a greater retracting amplitude of swing than desired, yet I prefer to provide a positive stop 45 for the rocker which will assure the engagement 45 of the tapered lip 39 with the sloping face of stud 33 even if the trigger should be permitted to rise above the point where it engages the stud.

By the construction illustrated and described, 50 it will be observed that trigger 38 has a component of motion in a direction transverse to the direction of valve opening and closing motion of the stem and that the trigger provides for a snap release of the stem. The snap release is obtained between two parts of which the trigger 55 is one and the wear-piece is the other, both of which are hard metal, and the lateral motion of the trigger with respect to the stem is a motion which is longitudinal of the second part, namely, is longitudinal of the wear-piece and 60 lever. By this arrangement I overcome any tendency to deform the valve stem, or to create any frictional resistance in the operation of the valve stem within the valve, and likewise, I avoid any 65 distorting tendency with respect to the lever since the motion of the trigger with respect to the lever is in a direction toward and away from the pivotal mounting of the lever. Furthermore, the thrust of the moving part 40 of the press upon the trigger is substantially in a longitudinal direction of the trigger and develops practically no wear or friction by side thrust within the supporting rocker. The greatest likelihood of wear exists between the sloping face of stud 33 and the tapered face of the lip 39 of the trigger, and 75

these parts are readily accessible for oiling purposes, and all parts concerned are readily replaceable, should occasion require replacement, with only a few minutes interval of time for 5 stopping the press being necessary.

I claim:

1. In combination with a valve having an operating stem or the like adapted to be depressed for opening the valve, of means for depressing 10 said stem from valve closing to opening position, said means comprising two parts of which one part is movable with the stem and of which the other part comprises a pivoted rocker member and a trigger slidable in said rocker member and 15 which is adapted to move transverse to the direction of depressing and effect a snap release of the first said part.

2. A valve operating mechanism comprising in combination with a valve having a valve stem, 20 a lever extending over said valve stem and pivoted at a distance from said valve stem, a pivoted rocker having a slidable depressing trigger one end of which is releasably engageable on said lever and slidable past said lever when released 25 therefrom, said trigger being thereby both pivotally and slidably mounted to engage the said lever during sliding movement of the trigger and arranged to slide off of the lever by the said swinging movement of the trigger.

3. In combination with a valve having a projecting stem, a trigger extending in the general direction of the stem, a pivotally mounted rocker slidably supporting said trigger, and a lever interposed between the stem and trigger for imparting motion from the trigger to the stem, said trigger being automatically releasable in consequence of swinging of said pivoted rocker from the depressing engagement against the lever when the stem has been depressed a predetermined distance which is less than the full stroke 40 of said trigger.

4. In combination with a valve having a projecting stem, a lever extending across the end of said stem and pivoted at a distance therefrom, said lever having an adjustable wear-piece on the upper side of said lever, a trigger projecting toward said wear-piece in the general direction of said stem, said trigger being mounted to slide toward and depress the said lever and being 50 mounted to swing in a direction away from the pivoting of said lever so as to slide off the end of said wear-piece and thereby permit the valve stem to rise as the trigger continues to depress, said adjustable wear-piece enabling the duration 55 of the depression of the stem to be altered at will.

5. A valve actuator comprising in combination with a depressible valve stem, mechanism successively depressing, holding and releasing said 60 stem comprising a trigger slidable in the same general directions as said stem, means on the end of said stem for receiving, depressing and holding thrust of said trigger when thereover and depressed, a pivoted rocker slidably mounting said trigger therein, said rocker having a lateral motion for enabling the trigger to snap off the edge of said means and release the stem, said trigger being retractable in the direction of movement of the stem when releasing and adapted to be swung back again when retracted over 65 said means and thereupon adapted to exert a thrust for again depressing said valve stem.

6. A valve actuator comprising in combination with a depressible valve stem, mechanism suc-

cessively depressing, holding and releasing said stem comprising a trigger slidable in the same general direction as said stem, means on the end of said stem for receiving, depressing and holding thrust of said trigger when thereover and depressed, a pivoted rocker slidably mounting said trigger therein, said rocker having a lateral motion for enabling the trigger to snap off the edge of said means and release the stem, said trigger being retractable in the direction of movement of the stem when releasing and adapted to be swung back again when retracted over 10 said means and thereupon adapted to exert a thrust for again depressing said valve stem, and a spring on the trigger tending to normally slide 15 the trigger to its retracted position.

7. A valve actuator comprising in combination with a depressible valve stem, mechanism successively depressing, holding and releasing said 20 stem comprising a trigger slidable in the same general direction as said stem, means on the end of said stem for receiving, depressing and holding thrust of said trigger when thereover and depressed, a pivoted rocker slidably mounting said trigger therein, said rocker having a 25 lateral motion for enabling the trigger to snap off the edge of said means and release the stem, said trigger being retractable in the direction of movement of the stem when releasing and adapted to be swung back again when retracted over 30 said means and thereupon adapted to exert a thrust for again depressing said valve stem, and a spring attached to the rocker tensioned to normally swing the rocker to draw the trigger laterally and position it over said means. 35

8. A valve actuator comprising in combination with a depressible valve stem, mechanism successively depressing, holding and releasing said 40 stem comprising a trigger slidable in the same general direction as said stem, means on the end of said stem for receiving, depressing and holding thrust of said trigger when thereover and depressed, a pivoted rocker slidably mounting said trigger therein, said rocker having a lateral motion for enabling the trigger to snap 45 off the edge of said means and release the stem, said trigger being retractable in the direction of movement of the stem when releasing and adapted to be swung back again when retracted over said means and thereupon adapted to exert a 50 thrust for again depressing said valve stem, and a spring attached to the rocker tensioned to normally swing the rocker to draw the trigger laterally and position it over said means, and a spring on the trigger tending to normally slide 55 the trigger to its retracted position.

9. A valve actuator comprising in combination with a depressible valve stem, mechanism successively depressing, holding and releasing said 60 stem comprising a trigger slidable in the same general direction as said stem, a pivoted lever having a portion thereof overlying said stem, said trigger being engageable at its end upon said lever for actuating the lever to depress said stem, a rocker slidably supporting said trigger enabling the trigger to swing and disengage said lever, and a stop in engagement with said trigger for guiding said trigger off of said lever as the trigger is slid in the general direction 65 of the stem and for guiding the trigger back onto the upper side of said lever when said trigger is retracted. 70

THEODORE J. BEREZH.
